THE NORRIS PETERS CO., PHOTO-LITHO., WASHINGTON, D. C.

UNITED STATES PATENT OFFICE.

EDWARD R. WAGNER, OF MILWAUKEE, WISCONSIN, ASSIGNOR TO E. R. WAGNER MANUFACTURING COMPANY, OF NORTH MILWAUKEE, WISCONSIN, A CORPORATION OF WISCONSIN.

METAL WHEEL-HUB.

SPECIFICATION forming part of Letters Patent No. 731,637, dated June 23, 1903.

Application filed February 20, 1903. Serial No. 144,200. (No model.)

To all whom it may concern:

Be it known that I, EDWARD R. WAGNER, a citizen of the United States, residing at Milwaukee, in the county of Milwaukee and State of Wisconsin, have invented certain new and useful Improvements in Metal Wheel-Hubs, of which the following is a specification, reference being had to the accompanying drawings, forming a part thereof.

10 This invention relates to hubs of the class shown and described in United States Letters Patent No. 719,282, dated January 27, 1903; and its main objects are to provide a hub of this class with means at its inner end for holding it on an axle and with a closure and guard at its outer end, thereby dispensing with a nut or other fastening at the outer end of the axle.

15 It consists in certain novel features of construction and in the arrangement and combinations of parts hereinafter particularly described, and pointed out in the claims.

20 In the accompanying drawings like letters designate the same parts in the several figures.

25 Figure 1 is a side view of a hub embodying my improvements, the spoke-flanges and one end of the barrel being shown in section. Fig. 2 is a cross-section on the line 2-2, Fig.

30 1. Fig. 3 is an end view showing the spoke-flange and closure at the outer end of the hub; and Figs. 4 to 9, inclusive, are detail views of the separate parts of which the spoke flange at the inner end of the hub is composed.

35 The hub herein shown and described is designed for use with an axle having a dog or detent to engage with an internal groove or channel in the inner end of the hub, and thereby hold the wheel in place on the axle without the usual nut or other fastening at the outer end of the axle-spindle.

40 Referring to Figs. 1 and 2, *a* is the hub-barrel, consisting of a straight metallic tube formed near its ends with external shoulders 45 or projections *b* for determining the position of the spoke-flanges and holding them thereon. At the outer end the hub is provided with a spoke-flange and fastening like or similar to that shown and described in the above-mentioned Letters Patent and consisting of

two disks *c* and *d*, fitted and secured on the barrel *a* and embracing the inner ends of the spokes *e*. The outer disk *d*, which is notched and clasped over the inner disk *c*, is formed with an outturned annular rim *f*. A circular convex plate *g*, preferably covered with rubber or other elastic or soft material to prevent marring furniture or other articles, is fitted and pressed tightly into place inside of the rim *f*, with which its periphery engages, thereby securely holding it in place. This plate forms a closure for the outer end of the hub, giving it a finished appearance, besides serving as a guard to prevent marring furniture and interior woodwork, this class of hubs being used mainly in baby-carriages.

The spoke-flange and fastening at the inner end of the hub is composed of two disks *h* and *i*, fitted on the barrel *a* and embracing the inner ends of the spokes *e* at that end of the hub, together with a notched circular band *j*. The disk *h* is preferably formed, like the disk *c*, with an outturned rim around its central opening to afford a wide bearing on the barrel and an abutment for the disk *i*. The disk *i* is formed with an outturned peripheral rim *k*. The band *j* fits on and surrounds the rim *k* on the disk *i* and is clasped at its inner notched end over the disk *h*. At its outer end it is formed with an inturned flange *l*, which abuts against and projects inwardly beyond the rim *k*, forming therewith an internal annular groove or channel for the engagement of the dog or detent which holds the wheel in place on the axle.

45 Various changes in the minor details of construction may be made without departing from the principle and intended scope of the invention.

I claim—

1. In a metal wheel-hub the combination with a tubular barrel and return-bend wire spokes, of a spoke-flange and fastening consisting of two disks fitted on said barrel and embracing the inner ends of the spokes, the outer disk having an outturned peripheral rim, and a band surrounding said disks, notched at its inner end and clasped over the inner disk and having at its outer end a flange which projects inwardly beyond and abuts 50

against the rim on the outer disk, forming therewith an internal annular channel, substantially as described.

2. In a metal wheel-hub the combination 5 with a tubular barrel and return-bend spokes, of a spoke-flange and fastening consisting of two disks fitted on said barrel and embracing the inner ends of the spokes, the outer disk having an outturned peripheral rim and the 10 inner disk having an outturned rim around its central opening, and a circular band surrounding said disks, notched and clasped at its inner end over the inner disk and formed at its outer end with a flange which extends 15 inwardly past the edge of the rim on the outer disk, forming therewith an internal annular channel, substantially as described.

3. In a metal wheel-hub the combination of a tubular barrel, having a spoke-flange and 20 fastening at one end composed of spoke-em- bracing disks, one of which is notched and clasped over the other, the outer disk having an outturned annular rim, a circular plate held by its periphery within said rim and 25 closing that end of the hub, and a spoke-flange and fastening at the other end of the hub,

composed of two spoke-embracing disks, the outer one of which has an outturned peripheral rim and a notched band surrounding 30 said disks, clasped over the inner disk and having an inturned flange which abuts against the rim on the outer disk and forms therewith an internal annular channel, substan- tially as described.

4. In a metal wheel-hub the combination 35 with a tubular barrel and wire spokes, of a spoke-flange and fastening consisting of two disks fitted and secured on said barrel and embracing between them the inner ends of the spokes and a circular band surrounding 40 said disks, notched and clasped over the inner disk, clamping both disks against the spokes, and having an inturned flange at its outer end forming with the outer disk an internal annular channel, substantially as de- 45 scribed.

In witness whereof I hereto affix my signature in presence of two witnesses.

EDWARD R. WAGNER.
